UNITED STATES PATENT OFFICE.

WILLIAM H. BENDERAGEL, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE-TRANSMISSION SYSTEM.

Application filed December 9, 1919. Serial No. 343,497.

To all whom it may concern:

Be it known that I, WILLIAM H. BENDERAGEL, a citizen of the United States, residing at Queens, in the county of Queens, State of New York, have invented certain new and useful Improvements in Telephone-Transmission Systems, of which the following is a full, clear, concise, and exact description.

- 10 This invention relates to a telephone transmission system. The object of the invention is to provide an amplifying repeater in a link or cord circuit of such a system.
- 15 One of the features of the invention is to provide two balancing lines for an amplifier at the answering end of the cord or link circuit, so as to balance the calling subscriber's line alone, or the calling line 20 and the operator's telephone line or set when the two are connected to the cord or ringing circuit. In the particular embodiment of the invention described and illustrated in this application, this is accomplished by 25 providing a balancing net-work consisting of two sections so arranged that one section may be used to balance the calling line, and the two sections will be automatically thrown in parallel to balance the calling 30 line and the operator's set when the operator's listening key is pressed.

Another feature of the invention is to connect the repeater in the cord or link circuit, and to provide battery for talking purposes to subscribers' lines which may be connected to either end of the cord circuit. In the embodiment shown, this is accomplished by splitting the repeating coil of a 35 cord circuit and connecting a battery for feeding the lines that are connected to each section, while the amplifier is connected in between the sections of the split repeating coil.

Another feature of the invention is to 40 provide a single relay which is both marginal and differential in a subscriber's cord circuit, and so connecting its windings that it may only be energized when both ends of the cord are plugged in line jacks to 45 render the amplifier active, and which may be de-energized by throwing the operator's ringing key. By rendering the amplifier inactive when the ringing keys are thrown, no singing of the amplifier will take place 50 due to unbalance between the various net-

works caused by opening the connected lines while ringing. Plugging in of one end of the cord is without effect on said relay whereby incoming calls which are merely inquiries and do not involve the establishment of a connection to another line or trunk do not place the amplifier in operation.

The invention will be understood from the description in connection with the accompanying drawing, which shows two subscriber's sets and a cord circuit which is provided with two one-way amplifiers, balancing sets, and the combined marginal and differential relay.

In the drawing, reference character A refers to a subscriber's line which is provided with the usual telephone set, line relay, line lamp, etc. When the subscriber at A raises his telephone hook, a circuit is closed through relay 1, thus closing its contact and lighting the line lamp L through an obvious circuit.

Upon noticing the signal at L, the operator inserts her plug P into the jack J of the calling subscriber's line, thus closing a circuit through the cut-off relay 2, thereby deenergizing the relay 1 and extinguishing the lamp L. The insertion of the plug P into the jack J also closes a circuit from battery through the upper half of the left-hand winding of transformer T, tip contacts of plug P and jack J, telephone set of subscriber A, ring contacts of jack J and plug P, relay 3, lower half of the left-hand winding of transformer T back to battery. This energizes relay 3, thereby closing its contact which permits current to flow through a circuit which may be traced from ground through relay 2, sleeve contacts of jack J and plug P, contact of relay 3, wire 4_a and coil a of relay 4, battery to ground.

Reference character 4 refers to a relay which is provided with three coils, a, b and c. The coils a and b are so designed that neither when energized alone is sufficient to operate the armature and contact. The coil c is wound so as to oppose the coils a or b and is such that current through the coil c will neutralize the energizing current through the coils a and b. Therefore when the plug P is inserted into jack J the relay 4 will not energize and the operator can, by throwing her listening key k, answer any inquiry of the calling subscriber without

affecting the amplifiers. When the operator desires to signal the called party, she inserts the plug P' into the jack J', and throws her ringing key K' or she may throw the 5 ringing key K' before inserting the plug. In either case the operation of key K' cuts off battery current from the subscriber B and simultaneously establishes a circuit from ground through battery, coil c, wire 4, 10 to ground, thereby preventing the operation of relay 4 and the closing of the circuit through the filaments of the amplifier, thus rendering the amplifiers inoperative. When the plug P' is inserted into the jack J', a 15 circuit is established from ground through relay 2', sleeve contacts of jack J' and plug P', lamp L', wire 4b, coil b, battery to ground, thus lighting the lamp L'. When the subscriber B raises his telephone hook, 20 as soon as the ringing key is returned to normal position a circuit is established from battery through the upper half of the right-hand winding of transformer T', tip contacts of plug P' and jack J', set of sub- 25 scribe B, ring contacts of jack J' and plug P', relay 3', lower half of the right-hand winding of transformer T' to battery. This energizes relay 3', thereupon short-circuiting the lamp L', and extinguishing the same. 30 The operator observing the retiring of the signal L', allows the ringing key to remain in normal position. As long as key K' was in the ringing position, winding c prevented windings a and b from operating the armature of relay 4. When the subscriber B raises his receiver and key K' is in normal 35 position so that 3' operates and L' becomes short-circuited, the current through b together with that from a is sufficient to operate the armature of relay 4. The operation of relay 4 establishes a circuit for the filaments of the repeater R and R', from battery, armature and contact of relay 4, conductor 5, filaments of R and R' in series to 40 ground.

The answering end of the cord or link circuit is provided with a balancing net-work N which consists of two sections, n and n₁, so arranged that the section n is in series 45 with the right-hand winding of transformer T and the primary of transformer t, thus operating as a balancer for the subscriber's set A when the plug P is in the jack J. When the operator presses her key k, her 50 telephone set is connected in parallel with the subscriber A and contact is made at k₁, thus connecting the section n₁ of net-work N in parallel with the section n, thereby providing a balancing net-work for both the 55 subscriber A and the operator's telephone set.

When both plugs are in their jacks and both telephone hooks are raised, talking current is supplied to both connected sub- 60 scribers from the batteries at transformers

T and T' as shown and the repeater is operative. With these connections, talking current from subscriber A passes through the jack J and plug P, relay 3, left-hand winding of transformer T and battery. At 70 the transformer T, it is transformed to the right-hand winding where it passes through the circuit including the primary of transformer t and section n of net-work N. At t₁ the current is transformed to the secondary 75 where it passes to the input side of amplifier R, and is amplified and passes to the output side of this amplifier to the circuit which includes the primary of transformer t', the net-work N' and the left-hand winding of transformer T', where it is transformed to the right-hand winding of transformer T' and thence passes through plug P' and jack J' to the subscriber B. Talking current from the subscriber B passes 80 through the connections in a similar way, except that it passes through and is amplified by the amplifier R' instead of the amplifier R.

When the subscribers at A and B hang up 90 their receivers, the circuits are broken through relays 3 and 3', thus permitting their contacts to open thereby removing the short-circuits from lamps L₁ and L', which light to give the operator the disconnect 95 signals. The operator then withdraws plugs P and P' from the jacks J and J', which deenergizes the relay 4 and opens its contact, thus rendering the amplifier inoperative and restoring the apparatus to normal 100 condition.

What is claimed is:

1. In a telephone exchange system, a plurality of subscriber's lines terminating at a central station, means for connecting said lines, said means comprising a repeater having a balancing network for one of said lines, a circuit, means for connecting said circuit to said means for connecting said lines, means whereby said balancing network 105 can be so modified as to make it capable of balancing both said one line and said circuit, and means for rendering said last mentioned means effective upon the connection of said circuit to said means for connecting said lines.

2. In a telephone exchange system, a plurality of subscriber's line circuits terminating at a central station, a link circuit, a repeater in said link circuit, an operator's telephone set, a balancing network for a subscriber's line connected to said link circuit, and means for changing the characteristics of said network when said operator's set is connected to said link circuit.

3. In a telephone exchange system, a plurality of subscriber's line circuits terminating at a central station, a link circuit, a repeater in said link circuit, an operator's telephone set, a balancing network comprising 120

- two branches connected to said link circuit, and means for changing the characteristics of said network when said operator's set is connected to said link circuit. 55
5. 4. In a telephone exchange system, a plurality of subscriber's line circuits, terminating at a central station, a link circuit, a repeater in said link circuit, an operator's telephone set, a balancing network comprising 60
- 10 two branches in parallel, one of said branches being connected to said link circuit and means for connecting said branches in parallel when said operator's set is connected to said link circuit.
- 15 5. In a telephone exchange system, a plurality of subscriber's line circuits terminating at a central station, a cord circuit, a repeater in said cord circuit, and a source of current in said cord circuit on either side of 65
- 20 said repeater for feeding connected subscribers' lines.
6. In a telephone exchange system, a plurality of subscriber's line circuits terminating at a central station, a link circuit, said 70
- 25 link circuit comprising a repeating path in each direction between said lines, each of said paths including a single amplifying stage, and sources of electromotive force in said link circuit at each end thereof for 75
- 30 feeding said subscribers' lines.
7. In a telephone exchange system, a plurality of subscriber's line circuits terminating at a central station, a link circuit, a repeater in said link circuit, a transformer 80
- 35 for connecting said repeater to one of said line circuits, a transformer for connecting said repeater to another of said line circuits, each of said transformers comprising only two inductively related windings, each 85
- 40 of said windings having all of its turns wound cumulatively, and one of said windings on each transformer being provided with battery for feeding connected lines. 90
8. In a telephone exchange system, a plurality of subscribers' lines, a link circuit, means for connecting said lines to said link circuit, means in said link circuit for signaling the connected lines, and a repeater in 95
- 45 said link circuit comprising an amplifying element rendered incapable of conducting current by the line connecting means and line signaling means. 100
- 50 9. In a telephone exchange system a calling and a called line terminating at
- a central station, a link circuit for connecting said lines, a repeater comprising an amplifying element in said link circuit, means in said link circuit for signaling the connected lines, and means controlled by said 55
- signaling means for rendering said amplifying element capable of conducting current. 60
10. In a telephone exchange system, a plurality of subscriber's line circuits terminating at a central station, a link circuit, comprising means for connecting said line circuits to said link circuit, a repeater in said link circuit, means in said link circuit for signaling the connected line circuits and a repeater controlling switch controlled by 65
- means. 70
11. In a telephone exchange system, a calling and a called line terminating at a central station, a link circuit, a repeater in said link circuit, and a combined marginal and differential relay for placing said repeater under the control of the connection of said link circuit with both of said lines and the disconnection of either of said lines. 75
12. In a telephone exchange system, a plurality of subscriber's line circuits terminating at a central station, a link circuit, a repeater in said link circuit, a balancing net-work for a subscriber's line connected to the answering end of said link circuit, and 80
- a battery at each end of said link circuit 85
- for feeding connected subscriber's lines. 90
13. In a telephone exchange system, a plurality of subscriber's line circuits terminating at a central station, a link circuit, a repeater in said link circuit, a repeating transformer in said link circuit for connecting said repeater to one of said line circuits, said repeating transformer having two 95
- inductively related windings, a source of direct current in circuit with only one of said windings for feeding said one of said line circuits, a repeating transformer in said link circuits for connecting said repeater to another of said line circuits and having two 100
- inductively related windings, and a source of direct current in circuit with only one of said last mentioned windings, for feeding said other line circuit. 105

In witness whereof, I hereunto subscribe my name this 5th day of December A. D., 1919.

WILLIAM H. BENDERNAGEL.
